JAMES C. DAWSON, OF WEBSTER GROVES, MISSOURI, ASSIGNOR TO ELMA N. DAWSON,
OF WEBSTER GROVES, MISSOURI

LOOSE-LEAF BINDER

Application filed January 3, 1927. Serial No. 158,445.

By custom each size of ring book binder has a standard diameter of wire for each diameter of ring, and a standard spacing for the rings. Each size of sheet of ring book paper has a standard punching, and the 5 diameter of the holes corresponds to the rings for one inch ring books. When, therefore, the number of sheets exceeds the capacity of a one inch ring book, two or more books must be used because the punching of the paper 10 prevents the sheets being transferred to a ring book of larger capacity.

An effort to overcome this limitation has been made by the use of tongue books 15 equipped with adjustable screws, but while this construction can be made to take any number of sheets the operation of inserting or removing the sheets is so tedious and time consuming that people of the type usually in 20 charge of such books will not keep them posted up to date.

The object of this invention is to provide a binder that will take standard paper and permit the capacity to be varied to suit conditions and the sheets to be removed or inserted with ease and celerity.

The fundamental organization includes 25 two separable binder bars equipped with two sets of posts, one set to extend through the perforations in the paper and the other set to bind the bars together and furnish the strength to the binder. The posts of the first set are relatively small and, being fixed close to the margin, can be received in the holes in 30 the paper and will permit the book to be opened wide. The posts of the other set are large and are made of such size as is necessary 35 to hold the binder bars in proper relation and relieve the smaller posts from strain. These 40 large posts are spaced back from the margins of the paper and have no effect upon the punching of the paper.

Other objects and advantages of the invention will become apparent as the description 45 proceeds and the description is read in connection with the accompanying drawings, in which,

Fig. 1 is a plan view of a binder embodying the invention, with certain parts at the 50 upper side broken away;

Fig. 2 is a transverse section taken on the line 2—2 of Fig. 1;

Fig. 3 is a longitudinal vertical section taken on the line 3—3 of Fig. 1;

Fig. 4 is a longitudinal horizontal section 55 of a portion of the binding bar shown in Figs. 1, 2 and 3;

Fig. 5 is a vertical section through an extensible binder post, which may be used in connection with the structures shown in Figs. 1, 2, 3 and 4;

Fig. 6 is a longitudinal vertical section through a different form of lock bar;

Fig. 7 is a longitudinal horizontal section 65 through the same;

Fig. 8 is a view similar to Fig. 1, illustrating another form of binder embodying the invention;

Figs. 9 and 10 are longitudinal and transverse vertical sections taken on the lines 9—9 70 and 10—10 of Fig. 8; and

Fig. 11 is a vertical sectional view of an extensible post that may be used in connection with the structure shown in Figs. 6 and 7.

In these drawings a bundle of sheets to be bound is shown at 10, between the leaves 11 and 12 of a cover, which are hingedly connected to the binder structure composed generally of upper and lower binder bars 13, 14, equipped with a set of small telescoping posts 80 15, and a set of large strong posts 16, which latter cooperate with a lock bar 17 to hold the bars 13, 14, in binding relation to the sheets 10.

An angular plate 18, secured to the binder bar 14 by the riveted bases of the posts 16, 85 has an upright portion 19 shielding and protecting the rear edges of the sheets 10 and cooperating with the lock bar 17 to give the binder a finished appearance. The covering material for the cover leaves is made to extend over the angular plate 18, as indicated at 20, and the locking bar 17, as indicated at 21.

The large posts 16 are reduced near their ends at 22 to cooperate with a locking slide 95 23, slidably mounted in the hollow lock bar 17, and moved into engagement with the posts by a screw 24 rotatably engaged with the slide and threaded in a nut 25 carried by the lock bar. The lower wall 26 of the lock bar is 100 perforated at 27 to receive the upper ends of

the posts and to bind against them when the latch bar is properly moved by the screw 24. As shown, the locking slide is provided with openings 28 larger than the posts, whereby it is adapted to pass freely over the posts in being put in place or removed.

The posts 15 are relatively small as compared with the posts 16, and are preferably composed of inner and outer telescoping sections A and B, the former being carried by the upper binder bar 13 and the latter by the lower binder bar 14. These posts can be made to suit any size of punching, and will be sufficiently strong in the selected size to retain within the binder a very large number of sheets, since most of the strain of holding the binder parts in proper relation will fall upon and be taken by the large posts 16.

When it is desired to fill such a binder the screw 24 is operated to move the locking slide 23 to released position, when that bar, with the leaf 11 and the binder bar 13, with its posts A, are removed. The sheets are placed upon the posts B, the binder bar 13 and the lock bar 17 are replaced, and the lock made fast.

Where found desirable this binder can be made extensible or adjustable by making the large posts 160 adjustable, as indicated in Fig. 5. The base section 29 is substantially the same as the post 16, except that it has no reduction corresponding to that shown in Fig. 2, and is provided with a threaded socket 30, which will receive a threaded stem 31 on a removable head piece 32, or any of a selected number of intermediate pieces 33. The telescoping posts 15 are inherently adjustable, and will permit the capacity of the book, equipped with such posts as shown in Fig. 5, to be varied widely.

In Figs. 6 and 7, the lock bar 34, corresponding to the lock bar 17 shown on sheet 1, is equipped with a different locking mechanism, including tilting latch pieces 35, normally held in the position shown in Fig. 6 by springs 36, but capable of being thrown upwardly to released position by inclined surfaces 37 on a releasing bar 38 slidably mounted in the lock bar and controlled by a handle 39. The latch pieces are perforated, as indicated at 40, to receive the upper ends of the large posts 41, which require no reduction. When the latch pieces are permitted to take the normal inclined position, they immediately bind against the posts and secure the lock bar in place. Upon bringing them into a substantially horizontal position in Fig. 6, they release the posts and permit the lock bar to be removed.

The posts 41 may be made sectional, as indicated in Fig. 11, where the base portion 42, fixed to the lower binder bar 14, may receive a threaded shank 43 on a head section 44, and a tubular intermediate section 45 may be

mounted on the threaded shank 43 when desired.

In the form shown in Figs. 8, 9 and 10, the upper and lower binder bars 13 and 14 are each secured to an angular bar 46 by the riveted bases of the telescoping posts 49 and the lock post 50, the upright portions 47 of which lie alongside of each other and together close the rear face of the binder mechanism. These pieces are enclosed within the covering material 48 and connected with the leaves 11 and 12 of the cover.

The posts 16 of sheet 1, and 41 of Figs. 6 and 7, are replaced by a set of telescoping posts 49, each composed of an outer tubular portion C, carried by the lower binder bar, and an inner portion D, carried by the upper angle member 46 and extending through the upper binder bar into telescoping relation with the section C. The upper angle member 46 corresponds to the lock bars 17 and 34, and therefore is a lock bar. The posts 49 are large and strong as compared with the posts 15. The perforations in the upper binder bar 13 fit snugly about the post sections D and communicate any stress on that bar directly to the large strong posts.

The lower binder bar carries an additional lock post 50, threaded internally to receive a long screw 51, having a head 52 for co-operation with a latch 53 slidably mounted on the upper angle piece 46 by headed pins 54, which extend through slots 55 in the latch. The intermediate portion of the latch has a keyhole slot 56, cooperating with the head of the screw to lock or release the parts in an obvious manner. By adjusting the screw 51 the capacity of the binder can be varied to suit conditions.

Generally speaking, the length of the post sections A and B, C and D, and the upright flanges 47 of the angle pieces, will be made to correspond and to permit adjustment within selected limits. In this form the upper angle member 46 corresponds to the lock bars used in the other forms.

It will be noted that in all forms the separable binder bars are equipped with one set of relatively small posts which extend through the perforations in the sheets, and are set near the front edges of the binder bars so as to permit the book to be opened wide. In addition the binder bars are equipped with a large strong set of posts which serve to take the strains that would otherwise be too much for the small posts. With such a construction sheets of paper having the standard punching for one-inch ring book binders can be used in any suitable quantity and can be readily removed and replaced.

I claim as my invention—

1. In a loose leaf binder, upper and lower separable binder bars, a set of small hollow posts carried by the lower binder bar adja-

cent to its front edge, a complemental set of small posts carried by the other binder bar and telescoping with the first set of posts, a set of large hollow posts projecting upwardly from the lower binder bar and spaced away from the small posts, a lock bar, a set of large posts projecting downwardly from the lock bar through the upper binder bar and telescoping with the other large posts, and means for making the lock bar fast.

2. In a loose leaf binder, upper and lower separable binder bars, a set of small hollow posts carried by the lower binder bar adjacent to its front edge, a complemental set of small posts carried by the other binder bar and telescoping with the first set of posts, a set of large hollow posts projecting upwardly from the lower binder bar and spaced away from the small posts, a lock bar, a set of large posts projecting downwardly from the lock bar through the upper binder bar and telescoping with the other large posts, a locking post projecting from the lower binder bar through the lock bar, and a latch on the lock bar engaging the locking post.

3. In a loose leaf binder, upper and lower separable binder bars, a set of small hollow posts carried by the lower binder bar adjacent to its front edge, a complemental set of small posts carried by the other binder bar and telescoping with the first set of posts, a set of large hollow posts projecting upwardly from the lower binder bar and spaced away from the small posts, a lock bar, a set of large posts projecting downwardly from the lock bar through the upper binder bar and telescoping with the other large posts, an extensible locking post projecting from the lower bar through the lock bar, and a latch on the lock bar engaging the locking post.

4. In a loose leaf binder, upper and lower separable binder bars, a set of small hollow posts carried by the lower binder bar adjacent to its front edge, a complemental set of small posts carried by the upper binder bar and telescoping with the first set of posts, a set of large hollow posts projecting upwardly from the lower binder bar and spaced away from the small posts, a lock bar, a set of large posts projecting downwardly from the lock bar through the upper binder bar and telescoping with the other large posts, a headed locking post projecting from the lower binder bar through the lock bar, and a latch bar on the lock bar having a keyhole slot for cooperation with the headed locking post.

5. In a loose leaf binder, upper and lower separable binder bars, a set of small telescoping posts mounted adjacent to the front edges of the bars and adapted to extend through perforations in the sheets to be bound, a set of large posts fixed to the lower binder bar beyond the margin of the sheets

to be bound, and means for connecting the other bar to one of the large posts.

6. In a loose leaf binder, upper and lower separable binder bars, a set of small telescoping posts mounted adjacent to the front edges of the bars and adapted to extend through perforations in the sheets to be bound, a set of large posts extending upwardly from the lower binder bar through the other binder bar, and locking means connected with one of the large posts to secure the bars together.

7. In a loose leaf binder, upper and lower separable binder bars, a set of small telescoping posts mounted adjacent to the front edges of the bars and adapted to extend through perforations in the sheets to be bound, a set of large posts extending upwardly from the lower binder bar through the other binder bar, and a locking bar above the other binder bar adapted to engage one of said large posts for preventing separation of the binder bars.

8. In a loose leaf binder, upper and lower separable binder bars, a set of small telescoping posts mounted adjacent to the front edges of the bars and adapted to extend through perforations in the sheets to be bound, a set of large posts extending upwardly from the lower binder bar through the other binder bar, and a locking bar above the upper binder bar, and means for making the locking bar fast to one of the large posts.

9. In a loose leaf binder, upper and lower separable binder bars, a set of small telescoping posts mounted adjacent to the front edges of said bars adapted to extend through marginal perforations in the sheets to be bound and to hold the sheets in place, and means for binding the bars including large posts spaced rearward from the small posts beyond the margin of the sheets and a lock above the upper binder bar engaging one of the large posts.

10. In a loose leaf binder, two binder bars between which the sheets are to be bound, a set of small posts carried by and extending between the bars adjacent to the front edges thereof and adapted to be received in the perforations in the sheets to hold them in the binder, and a set of large posts carried by one of the bars and extending through the other bar and located rearward from the first set of posts and means detachably associated with one of the large posts for holding the other binder bar in place.

11. In a loose leaf binder, upper and lower binder bars, two sets of posts, one set of posts being relatively small and carried by and extending between the binder bars and mounted adjacent the front edges of the bars to extend through the perforations in the sheets to be bound, the other set of posts being relatively large and carried by one of the binder

bars and located beyond the margins of the sheets to be bound, and means comprising a lock bar and locking means carried by the lock bar and engaging one of the large posts and adapted to secure the binder bars together.

In testimony whereof I affix my signature.
JAMES C. DAWSON.
